STARTING AND IGNITION SYSTEM FOR INTERNAL-COMBUSTION ENGINES.

1,337,649.

Specification of Letters Patent. Patented Apr. 20, 1920.

Application filed March 7, 1918. Serial No. 221,068.

To all whom it may concern:

Be it known that I, VALÈRE A. FYNNE, a subject of the King of England, residing at the city of St. Louis, State of Missouri, United States of America, have invented a certain new and useful Starting and Ignition System for Internal-Combustion Engines, of which the following is such a full, clear, and exact description as will enable any one skilled in the art to which it appertains to make and use the same, reference being had to the accompanying drawings, forming part of this specification.

My invention relates to a battery ignition system for internal combustion engines operated in conjunction with a cranking motor receiving energy from the battery to start the engine. It often happens that the cranking motor is started before the ignition switch is closed—in which case, all the energy expended in cranking the engine is wasted and the battery is uselessly drained to a corresponding extent. It is usual to provide such ignition systems with a hand operated ignition switch and to lock same in its off position when storing the car in the garage, or when parking it. But the car can nevertheless be propelled even when the ignition switch is locked in the manner described, for it is only necessary to throw in the gears and close the starting switch when the car will be moved by means of the cranking motor to the great detriment of the battery. This practice is resorted to by automobile thieves and frequently by garage employees in the absence of the owner.

The object of my invention is to preclude the possibility of wasting the battery energy in cranking the motor with the ignition circuit open and to make it impossible to crank the engine or to start the cranking motor when the ignition switch is locked in its off position by means of a Yale lock or some other device. My invention has the further advantage of preventing accidental closing of the motor starting switch when the engine is in operation.

In carrying out my invention, I provide interlocking means between the ignition and starting switches so arranged as to make it impossible to start the cranking motor unless the ignition switch is in its operative position. My invention will be better un-

derstood by reference to the accompanying drawing, in which Figure 1 is a diagrammatic representation of one embodiment of my invention, while Fig. 2 diagrammatically indicates the side elevation of the ignition switch of Fig. 1.

One pole of the battery 12 is connected to the terminal 2 on which the lever 8 of the ignition switch is pivoted. The other pole is connected to the low tension side of the spark coil 11 and through it to the timer 10 and the stationary contact 1 adapted to coöperate with the ignition switch. The high tension side of the ignition coil is grounded at one end and connected to a distributor at the other. The positive pole of the battery is also connected to the spring controlled starting switch 21. The spring 20 normally holds this switch against the stop 19. That pole of the battery which is connected to the spark coil is also connected to the field winding 26 of the cranking motor and through its armature 25 to the stationary contact 23 adapted to coöperate with the starting switch 21. The switch arm 21 carries a pin 18 adapted to engage the nose 22 provided on the disk 24 pivoted at 28 and held in the position indicated in the figure by means of the spring 16. In order to close the starting switch 21, it is necessary for the pin 18 to move the nose 22 out of its normal position, thus revolving the disk 24 in a counter-clockwise direction. The pin and the nose are so correlated that when the switch 21 is closed, they are still in engagement. A movement of the disk 24 in a counter-clockwise direction is, however, prevented by means of the catch 14, which engages with the notch 17 when the disk is in its normal position. This catch is firmly held in the support 15, but can be lifted out of engagement with the notch 17 by means of the electromagnet 13, one terminal of which is connected to the negative pole of the battery, whereas the other is connected to the stationary contact 3, adapted to coöperate with the movable spring controlled contact 7, supported by the arm 8 of the ignition switch. When the ignition switch has been moved to its closed position, for instance, by means of the handle 9, then connection is established by it between the contacts 2 and 4 and while contact 7 is now in a position to coöperate

with the contact 3, yet it is held away from the latter by means of the spring 6 secured by the screw 5. When the ignition switch is closed, the circuit of the electromagnet 13 can be closed by pressing on the contact 7. The energizing of this electromagnet lifts the catch 14 out of engagement with the notch 17 and allows the starting switch to be moved to the stationary contact 23, thus closing the circuit of the cranking motor.

In operating the arrangement shown, it is first necessary to close the ignition switch, then to press on the contact 7 and to close the starting switch. As soon as the starting switch has been closed, the contact 7 may be released. This will deenergize the electromagnet 13 and allow the catch 14 to rest on the disk 24 at some point to the right of the notch 17. When the engine has fired and is able to operate without the help of the cranking motor, the switch 21 may be released when the disk 24 will return to its normal position and allow notch 17 to again engage with the catch 14. In order to stop the engine, the ignition switch is opened and may be locked in its off position in any desired manner. When so locked, it will be impossible, because of the catch 14 and the notch 17, to close the circuit of the cranking motor.

This arrangement permits the motor switch to be operated by the foot, as is now usual, and of the said switch being located close to the cranking motor and to the battery, thus reducing to a minimum the length of the heavy connecting cables necessary for the cranking circuit.

Having fully described my invention, what I claim as new and desire to secure by Letters Patent of the United States is:

- 40 1. In a starting and ignition system for internal combustion engines, a starting motor, a supply circuit therefor, an ignition circuit, an ignition controlling switch, means for controlling the closing of the supply circuit, said means comprising a manually operable switch which can be opened and closed only when the ignition switch is in its closed position.
- 50 2. In a starting and ignition system for internal combustion engines, a starting motor, a controlling switch therefor, an ignition circuit, a controlling switch for said circuit, locking means preventing the closing of the motor switch, and means operable only when the ignition switch is in closed position for releasing the locking means.
- 60 3. In a starting and ignition system for internal combustion engines, a starting motor, a controlling switch therefor, an ignition circuit, a controlling switch for said

circuit, locking means preventing the closing of the motor switch, electromagnetic means for releasing the locking means, a pair of contacts for controlling the electromagnetic means, one of said contacts being movable by the ignition switch out of operative relation with the other.

4. In a starting and ignition system for internal combustion engines, a starting motor, a controlling switch therefor, an ignition circuit, a controlling switch for said circuit, locking means preventing the closing of the motor switch, electromagnetic means for releasing the locking means, a pair of contacts for controlling the electromagnetic means, one of said contacts being mounted on the ignition switch arm.

5. In a starting and ignition system for internal combustion engines, a starting motor, a controlling switch therefor, an ignition controlling switch, a pivoted locking member in the path of the motor controlling switch, a stop coöperating therewith, and means for removing said stop from engagement with the pivoted member, said means being operable only when the ignition switch is closed.

6. In a starting and ignition system for internal combustion engines, a starting motor, a controlling switch therefor, an ignition controlling switch, a pivoted locking member in the path of the motor controlling switch, a stop coöperating therewith, means for removing said stop from engagement with the pivoted member, said means being operable only when the ignition switch is closed, and means for bringing said stop and pivoted member into engagement when the motor controlling switch is open.

7. In a starting and ignition system for internal combustion engines, a starting motor, a controlling switch therefor, an ignition controlling switch, a movable locking member in the path of the motor controlled switch, and means controlling said locking member, said means being operable only when the ignition switch is closed.

8. In a starting and ignition system for internal combustion engines, a starting motor, a controlling switch therefor, an ignition controlling switch, a movable locking member in the path of the motor controlled switch, and means controlling said locking member, said means being operable only when the ignition switch is closed and comprising an electromagnetically controlled stop coöperating with the locking member.

In testimony whereof I have hereunto set my hand and affixed my seal.

VALÈRE A. FYNN. [L. S.]
